ELECTRICAL DUCT

John B. Cataldo, Birmingham, Mich., assignor to BullDog Electric Products Co., Detroit, Mich., a corporation of West Virginia

Application October 18, 1954, Serial No. 32,705

Term of patent 14 years

(Cl. D54—2)

Fig. 1 is a perspective view of an electrical duct showing my new design.

Fig. 2 is a top plan view thereof.

Fig. 3 is a side elevational view; and

Fig. 4 is an end view of the electrical duct.

The design is of arbitrary overall length.

I claim:

The ornamental design for an electrical duct, as shown and described.
